(57) **CLAIM**

The ornamental design for a combined water dispenser and tray, as shown and described.

DESCRIPTION

FIG. 1 is a left front perspective view from above of a combined water dispenser and tray showing our new design; FIG. 2 is a front elevational view of the combined water dispenser and tray of FIG. 1;

FIG. 3 is a rear elevational view of the combined water dispenser and tray of FIGS. 1 and 2;

FIG. 4 is a left side elevational view of the combined water dispenser and tray of FIGS. 1-3;

FIG. 5 is a right side elevational view of the combined water dispenser and tray of FIGS. 1-4;

FIG. 6 is a top plan view of the combined water dispenser and tray of FIGS. 1-5;

FIG. 7 is a bottom plan view of the combined water dispenser and tray of FIGS. 1-6;

FIG. 8 is a right front perspective view from above of the combined water dispenser and tray of FIGS. 1-7 and showing a state where an internal water tray is empty and a buoy sinks to the bottom; and,

FIG. 9 is a right front perspective view from above of the combined water dispenser and tray of FIGS. 1-7 and showing a state where the water tray is full and the buoy floats. The areas shown in broken lines and masked in white form no part of the claimed design.
